UNITED STATES PATENT OFFICE.

ALMER McDUFFIE McAFFEE, OF NEW YORK, N. Y., ASSIGNOR TO GULF REFINING COMPANY, OF PITTSBURGH, PENNSYLVANIA, A CORPORATION OF TEXAS.

MANUFACTURE OF HIGH-GRADE LOW-BOILING PETROLEUM PRODUCTS.

1,326,073.

Specification of Letters Patent. Patented Dec. 23, 1919.

Application filed January 9, 1915. Serial No. 1,375.

To all whom it may concern:

Be it known that I, ALMER McDUFFIE McAFFEE, a citizen of the United States, residing at New York, in the county of New York and State of New York, have invented certain new and useful Improvements in the Manufacturing of High-Grade Low-Boiling Petroleum Products, of which the following is a specification.

- 10 This invention relates to the manufacture of high-grade low-boiling petroleum products; and it comprises a method wherein higher boiling petroleum oils or products are subjected to a cracking operation to 15 produce vapors of lower boiling products, such cracking operation being at ordinary pressure or under as much added pressure as may be desired; the vapors are led into contact with a heated body of oil containing 20 aluminum chlorid, such body of oil being oil condensed from such vapors or being oil from another source, or both; and the vapors coming from said heated body are then condensed in a suitable manner; 25 all as more fully set forth and described.

The fact that the commercial demand for the lower boiling petroleum oils, gasolene, and naphtha or solvent oils, such as the "turpentine substitutes," is greater than 30 that for the higher boiling oils has of course led to the proposal of many methods for converting high boiling into low boiling oils. The most common method now in use is "cracking" which involves heating high 35 boiling residual oils or distillates to a temperature at which they will break up or dissociate. By the use of pressure the temperature to which liquid oil can be heated is of course increased and the cracking 40 operation is thereby rendered more productive of "cracked" low boiling oils and products. A greater yield of gasolene can be obtained. In practice, the crude petroleum is first freed by ordinary distillation 45 of the natural gasolene (if any) and kerosene which it contains, and then the distillation is continued under cracking conditions and at a high temperature; often under high pressure. A further portion of "cracked" 50 gasolene and kerosene appears as a result of this distillation; and under proper conditions a rather large percentage of the residual oil can be so converted into gasolene and kerosene. The same cracking operation for the production of gasolene is often

applied to gas oil and other low grade distillates.

These cracked distillates however are of comparatively low grade; they are not nearly so desirable as the "natural" gasolene and kerosene obtained by simple distillation of crude oil. This low quality is mostly due to the fact that they are largely composed of unsaturated oils or hydrocarbons; hydrocarbons which, chemically considered, do not contain enough hydrogen to saturate the carbon. Unsaturated oils are foul-smelling, burn with smoky flame and darken on standing or exposure to air. Purification of these cracked distillates by 60 the ordinary method adapted with natural oils and distillates, that is, treatment with sulfuric acid, is expensive since the loss of oil and the consumption of acid are inordinately great. Unsaturated oils combine 65 with sulfuric acid with readiness.

Another method of producing low-boiling oils from high boiling oils which gives gasolene of much higher grade involves the use of aluminum chlorid. Aluminum chlorid 70 exercises a number of distinct actions upon the hydrocarbons which constitute petroleum oils and petroleum products. It is capable of producing intermolecular and intramolecular rearrangements, which may be 75 utilized in making lower boiling oils from higher boiling oils, as in making gasolene from gas oil, etc. Another action is the production of saturated hydrocarbons from unsaturated with deposition of carbon. When high boiling petroleum oils are admixed with aluminum chlorid and the mixture is kept at the distilling or boiling temperature, say 470° F. or higher, a distillate is produced which, under proper conditions, is a clean, sweet, saturated gasolene 80 requiring little or no treatment with acid to make a commercial high-grade material. Ordinarily treatment of the distillate with acid for the purpose of removing unsaturated compounds is neither needed nor used. In order to accomplish these results, the operation should be so conducted that a partial refluxing of condensed vapors back to 85 the boiling mixture occurs and the temperature of the vapors at the point where they leave the vapor producing system to enter the final condensing system should not be above 350° F. If the vapors reach the final condensing system at a higher temperature, 90

not only is the condensate impaired by the presence of undue amounts of high boiling fractions but aluminum chlorid (or its compounds with the hydrocarbons of the oil) is also apt to pass over into the condenser. This not only removes the chlorid from the place where it is needed but stops up the condenser. Also the distillation should be carried on comparatively slowly; the heating should be so conducted as to spread the distillation over, say, 48 hours.

The described method may be used for converting any higher boiling petroleum oil or product into lower boiling products; as for example in converting kerosene into gasoline or naphtha. It may be advantageously used in converting higher boiling portions of crude petroleum or its products into gasoline, or gasoline, naphtha and kerosene. For example, residual petroleum oils or low grade distillates, such as gas oil, solar oil, etc., may be so converted.

In using aluminum chlorid the oil must be dry. As a rule about 5 per cent. of aluminum chlorid, calculated on the weight of oil, is used, but greater or less amounts may be employed. A charge of chlorid may be continuously employed until it is converted into a granular coky mass of little activity and be then removed and replaced by fresh reagent. Charging and discharging may be continuous or discontinuous. If the temperature at the point of vapor exit to the condenser be held around 350° F., the condensate will be a mixture of gasoline, naphtha and kerosene which may be redistilled to separate and obtain these products; but if the vapor temperature be held somewhat lower, say at about 300° F., the distillate will be practically all gasoline. If the vapor temperature at the exit from the vapor producing system be held still lower, at, say, 200° to 250° F., a highly volatile gasoline of uniform character may be obtained. By continuing the distillation of a charge of oil to the end about 85 per cent. or more may be converted into gasoline, or gasoline, naphtha and kerosene, as the case may be; the 15 per cent. or so difference representing gas and coke. Even when using low grade crudes, by interrupting the distillation after a substantial amount of low boiling oils has been distilled over but when a substantial amount of high boiling oil remains in the still, the latter is fit for the manufacture of high grade lubricants, medicinal oils, paraffin, etc., asphaltic constituents, sulfur, etc., having been removed or converted into other products.

The action of aluminum chlorid on oils in the described method is, as stated, twofold. It has a saturating action, converting unsaturated hydrocarbons into saturated, and it also has a converting or breaking down action by virtue of which it transforms

high-boiling oils, under the distilling conditions stated, into low-boiling oils. The saturating action is attended with a deposition of carbon; the aluminum chlorid finally being converted into a coky sludge from which it may be regained for reuse by suitable methods (see McAfee Patent No. 1099096, granted June 2, 1914). Other decarbonizing catalysts than aluminum chlorid may be used, such as for example aluminum in the presence of hydrochloric acid, aluminum in the presence of chlorin, aluminum bromid, ferric chlorid, zinc chlorid, etc., but they are not generally as advantageous.

By a modification of the described method I may also materially improve the quality of these cracked gasolines in other respects than the conversion of the unsaturated into the saturated hydrocarbons. There is a demand for gasoline distilling within a narrower temperature range than that of ordinary gasoline which, as it now occurs on the market, may begin to distil at 120° F. and end at a distilling temperature of 350° F. In so doing I take advantage not only of the property of aluminum chlorid of converting unsaturated into saturated bodies, but also of its property of converting higher boiling oils into lower boiling. For this purpose I operate at a somewhat higher temperature in treating the mixture of gasoline and aluminum chlorid than that just described. This higher temperature produces more or less distillation and I control this distillation in a special way. This treatment may not only be applied to the commercial "cracked gasolines" but also to the cracked distillates from which these cracked gasolines are made by redistillation. These cracked distillates begin to boil at about 120° F. and have a final boiling point of about 500° F. or possibly above. To this end I mix the material with aluminum chlorid as before and heat to the boiling temperature of the mixture under such conditions as will permit a refluxing of vapors of high boiling, or heavy, portions or fractions. The vapors may be allowed to pass to the final condensing system at a temperature between 200° F. and 250° F. The product here is, as before, a clean sweet gasoline but it is of more uniform characteristics than the original, having a closer distillation range.

In the present invention I operate on the vapors coming from a petroleum still, advantageously one in which cracking distillation is being performed, and subject these vapors to the action of aluminum chlorid immediately after their formation. In such an embodiment of my process I may crack a suitable high boiling oil in a suitable apparatus; advantageously using a pressure up to, say, 4 to 6 atmospheres; that is, 60 to 90 pounds. This pressure may be that due to the vapors formed in the still or to

vapors or gases pumped into the still into or over the distilling mass. The oil treated may be a residual crude petroleum from which low boiling fractions have been removed; or it may be one of the low grade distillates sold as gas oil, solar oil, etc., or, but less advantageously, straight crude oil. The vapors leaving the still and passing a suitable pressure reducing valve may be directly contacted with aluminum chlorid in any suitable receptacle. This receptacle is best heated although this is not always necessary. Under the described conditions, high boiling constituents in the vapors condense and form an oil pool or body containing the aluminum chlorid. The low-boiling constituents of the vapors are converted in this bath or body of aluminum chlorid-oil mixture into saturated products and pass onward to a suitable condenser to give gasoline. Between the aluminum chlorid mixture and the condenser is interposed any suitable reflux means which will return vapors of aluminum chlorid, of high boiling oils, etc. As previously stated, the temperature to be maintained at the entrance to the condensing system may be between 300° and 350° F.; the precise temperature depending upon the product sought. For very volatile, highly uniform gasoline the temperature at this point is advantageously even lower; say, between 200° and 250° F. The high boiling oil of the oil body, or aluminum chlorid-oil mixture, is constantly changing under the converting action of the aluminum chlorid, being converted into gasoline which distils over. New portions of high boiling oil condense and keep the volume of the oil replenished.

In the described operation, substantially I am treating the vapors from a cracking still or element with aluminum chlorid; I am interposing an aluminum chlorid treatment between the ordinary cracking still and the ordinary condenser.

I may also combine the improvement of the cracked distillates with the aluminum chlorid method of producing gasoline heretofore described. In this embodiment of my invention I produce cracked oil vapors in the manner previously described and pass these vapors directly into a hot boiling mixture of high boiling oil and aluminum chlorid; this high boiling oil being from another source. For example, I may provide a charge of gas oil and aluminum chlorid in a suitable still and bring it up to the boiling point for the production of the described saturated gasoline. Another charge of gas oil is contained in an ordinary cracking still, which may be operating under heavy pressure, and the vapors from this cracking operation are led directly into the boiling mass of oil and aluminum chlorid.

The saturating action of aluminum chlorid

is here more rapid than its gasoline-producing action and in this manner of operation without changing the normal operation of the gasoline-producing still, so far as the action of the aluminum chlorid upon the charge of high boiling oil therein contained is concerned, I can materially increase its output. A much larger amount of gasoline vapor is delivered to the condenser in a given time in using a given still. Part of this gasoline comes from the transforming action of the chlorid upon the high boiling oil charge; part comes from the cracked vapors fed in; but it is all uniform, clean, good quality saturated gasoline.

The vapors from the cracking still are, as usual, rich in high boiling oils vaporized at the high temperatures employed, and are also largely unsaturated. In passing through the oil-chlorid mixture the high boiling oils are condensed and join the mixture while the unsaturated low boiling compounds are saturated and pass on.

In the accompanying illustration I have shown, more or less diagrammatically, partly in elevation and partly in vertical section, an assemblage of apparatus elements for use in the described process. In this showing, element 1 is a cracking still or other source of cracked oil vapors of any suitable construction and heated in any ordinary manner. It is provided with the gage 2 and the safety valve 3. The vapors produced in the still pass through the vapor line 4, past a throttling or a pressure reducing valve 5 to an annular perforated pipe 6 situated near the bottom of an aluminum chlorid still 7. As shown, this still is provided with stirring means 8 carrying chains 9. Within the still is a body 10 of a mixture of high boiling oil and aluminum chlorid. Vapors from this still pass through the conduit 11 to air cooled condensing chamber 12, which operates to reflux aluminum chlorid vapors, etc. Beyond this chamber the vapors pass through conduit 13 to another air cooled reflux device 14, and thence through the conduit 15 to a third air cooled chamber 16. These latter two chambers communicate at their bottoms, respectively, through 17 and 18 with a conduit 19 leading back to the still. In this latter conduit is a depression 20 which serves as a trap. The inlet 21 serves for introducing fresh oil. Manhole 22 serves for introducing fresh aluminum chlorid, cleaning, etc. The manhole 23 may be used in cleaning the still, removing chlorid sludge, etc. The valve pipe 24 may be used for removing oil. The diagrammatically shown furnace 25 serves for heating. The vapors which leave the last named chamber (16) pass through conduit 26 past thermometer 27 into a condenser of usual type 28 contained in the cooling tank 29.

In the use of the described apparatus the

cracking still 1 may be charged with a body of any suitable petroleum material whether crude oil, residual oil or a distillate oil, and heated until the pressure shown by the gage 5 reaches the desired point. The pressure may be advantageously 60 pounds to 90 pounds, that is four to six atmospheres, or even higher. Pressures ranging up as high as 300 pounds may be employed but ordinarily pressures of four to six atmospheres are better. Cracked gasoline vapors pass out from the still through 4, the pressure in the still being maintained by suitable manipulation of valve 5. The vapors from 4 pass into the aluminum chlorid still or chamber 7 through the perforated pipe 6. This still contains a charge of aluminum chlorid. It may be fed with gas oil or other suitable oil through inlet 21 from time to 10 time or in starting. Or the condensate from the cracked oil vapors may be relied upon. In either event a pool 10 of a mixture of heavy oil and aluminum chlorid is formed. This pool may be maintained at a distilling 15 temperature by the diagrammatically shown firing means 25, or the temperature in still or chamber 7 may be kept up by the heat of the vapors from element 1. Element 1 in lieu of being a still may be a mere receptacle for cracked oil vapors produced elsewhere. Vapors of saturated gasoline, both that produced by the conversion of the vapors from 4 and the conversion of the oil 20 of the oil body 10 pass upward through the elements 12, 14 and 16 from which condensates drain back to the chamber 7. The operation is so conducted that the temperature of the vapors passing through 26, as shown by thermometer 27, is not above 350° F. or 25 such temperature as will prevent the carrying of aluminum chlorid into the condenser. It may be much below this temperature as previously stated. The vapors going to exit from the distilling system at 26 pass into 30 condenser 28 and give liquid low boiling saturated products. As stated, the liquid gasoline here formed does not necessarily require acid treatment to make it marketable, being a substantially saturated product.

35 While I have hereinbefore more particularly described the application of this invention to the treatment of cracked oil vapors, I obtain many of the same advantages by treating other oil vapors produced by simple distillation without steam. For example, oil vapors from distilling crude petroleum in the ordinary way may be passed through a pool or body of a heated mixture of high boiling oil and aluminum chlorid. In so 40 doing, the lower boiling oils, so far as they are saturated, pass onward to the condenser, while unsaturated low boiling oils, if any are present, are converted into saturated and also go to the condenser. The high boiling portions of the oil vapors are condensed

in the oil pool and undergo the described converting operation. I regard my invention as particularly applicable to the treatment of vapors from oil stills run at a high temperature, whether the operation in such still be cracking distillation in the ordinary sense of the term or any other type of high temperature distillation. The greatest advantages of my invention are obtained however in treating cracked oil vapors.

70 What I claim is:—

1. In the manufacture of low boiling petroleum products of high grade the process which comprises subjecting a petroleum material to a cracking operation and subjecting 80 the evolved vapors to the action of aluminum chlorid in sufficient amount to convert unsaturated compounds into low boiling saturated compounds.

2. In the manufacture of low boiling petroleum products of high grade, the process which comprises subjecting a petroleum material to a cracking operation and subjecting the evolved vapors to the action of aluminum chlorid in the presence of a body 85 of high boiling oil.

3. In the manufacture of low boiling petroleum products of high grade, the process which comprises subjecting a petroleum material to a high temperature distilling operation and subjecting the evolved vapors to the action of aluminum chlorid in the presence of a body 90 of high boiling oil.

4. In the manufacture of low boiling petroleum products of high grade, the process 100 which comprises subjecting a petroleum material to a cracking operation and subjecting the evolved vapors to the action of aluminum chlorid in the presence of a heated body of high boiling oil.

5. In the manufacture of low boiling petroleum products of high grade, the process which comprises subjecting a petroleum material to a cracking distillation and subjecting the vapors to the action of aluminum 110 chlorid in the presence of a heated body of high boiling oil from another source.

6. In the manufacture of low boiling petroleum products of high grade, the process which comprises distilling a high-boiling oil in admixture with aluminum chlorid and during the distilling operation passing through the boiling body of such mixture a current of cracked oil vapors.

7. In the manufacture of low boiling petroleum products of high grade, the process which comprises distilling a high boiling oil in admixture with aluminum chlorid and during the distilling operation passing through the boiling body of such mixture a current of oil vapors from another source.

8. The process of making saturated gasoline which comprises distilling a body of high boiling oil under cracking conditions, passing the vapors therefrom into a cham-

75

ber containing aluminum chlorid and into contact with said aluminum chlorid, and withdrawing and condensing vapors from said chamber.

5 9. The process of making saturated gaso-
lene which comprises distilling a body of
high boiling oil under cracking conditions
to produce cracked gasoline vapors, passing
said vapors into a heated chamber contain-
10 ing aluminum chlorid and into contact with
said aluminum chlorid, and withdrawing
and condensing vapors from said chamber.

10 10. The process of making saturated gaso-
lene which comprises distilling a body of
15 high boiling oil under high pressure, re-
leasing the pressure on the vapors, passing
said vapors into a chamber containing alu-
minum chlorid and into contact with said
aluminum chlorid, and withdrawing and
20 condensing vapors from said chamber.

11. The process of making saturated gaso-
lene which comprises distilling a body of
high boiling oil under a pressure of four to
six atmospheres, releasing the pressure on
25 the vapors, passing said vapors into a cham-
ber containing aluminum chlorid and into
contact with said aluminum chlorid, and
withdrawning and condensing vapors from
said chamber.

30 12. In the production of saturated gaso-
lene, the process which comprises establish-

ing and maintaining a boiling body of a
mixture of high boiling oil and aluminum
chlorid while constantly removing and con-
densing gasoline vapors therefrom and con-
stantly introducing vapors of cracked gaso-
lene thereinto. 35

13. In the production of saturated low
boiling petroleum products, the process
which comprises establishing and maintain-
40 ing a boiling body of a mixture of high boil-
ing oil and aluminum chlorid while con-
stantly removing and condensing vapors of
low boiling products therefrom and con-
stantly introducing vapors of cracked oil 45
thereinto.

14. In the production of saturated gaso-
lene, the process which comprises establish-
ing and maintaining a boiling body of a mix-
ture of high boiling oil and aluminum 50
chlorid while constantly removing and con-
densing gasoline vapors therefrom at a
temperature not above 350° F. and con-
stantly introducing vapors of cracked gaso-
lene thereinto. 55

In testimony whereof, I affix my signature
in the presence of two subscribing witnesses.

ALMER McDUFFIE McAfee.
